UNITED STATES PATENT OFFICE.

JOHN GILLESPIE, OF BOSTON, MASSACHUSETTS, ASSIGNOR TO GEORGE M. PORTER, OF SAME PLACE.

BICYCLE.

SPECIFICATION forming part of Letters Patent No. 573,779, dated December 22, 1896.

Application filed April 6, 1896. Serial No. 586,338. (No model.)

To all whom it may concern:

Be it known that I, JOHN GILLESPIE, of Boston, in the county of Suffolk and State of Massachusetts, have invented certain new and useful Improvements in Bicycles, of which the following is a specification.

My invention relates to the shaft to which the crank is attached; and it consists in making the said shaft in two parts, fitted to each other on an oblique line, the object being to avoid the necessity of attaching the crank to the shaft, as is now done, by means of keys, check-nuts, and washers, and at the same time to enable the cranks to be easily removed by a person of little mechanical skill or knowledge. The cranks are attached to the shaft by being brazed thereto and are removed with the portion of the shaft to which they are respectively attached. A perfect-fitting joint is formed by means of frictional contact only of the two parts of the shaft.

I have shown in the drawing a sectional view of my invention.

a a are the pedals.
25 *a' a'* are the cranks attached to one end of the shaft *b b'*. The shaft is made in two parts and is provided with the cone *c*, screwed thereto and resting on the ball-bearings *d d*.
30 *f f* are adjusting-nuts, by means of which the bearing against the balls may be adjusted. The cones *c* and the adjusting-nuts *f* are provided, respectively, with a right and left screw-thread, so as to prevent any loosening of the joint. The shaft *b b'*, made in two parts, as stated, has the plane of its longitudinal meeting surfaces made on a line oblique

to the axis of the shaft, as shown at *e*. It will be seen that when the two parts are fitted together each will press against the opposite surface of the other, and also bear against the 40 inner surface of the sleeve *g*, this constant pressure being caused by the action of the planes of the two longitudinal meeting surfaces, which are placed, as stated, on a line oblique to the axes of the two parts of the 45 shaft *b b'*. The two parts of the shaft are made hollow, as shown in the figure by the broken lines, one section being made hollow throughout and the other having a solid portion at the end, the object being to enable 50 the shaft to be separated by driving apart the sections by a rod inserted in the hollow section in case the two parts thereof should bind. In such case a small piece of metal is to be inserted, and a slight blow thereon will 55 separate the two parts of the shaft, so that they may be easily taken out.

What I claim, and desire to secure by Letters Patent, is—

In a bicycle, a crank-shaft made in two 60 parts each of which has an inclined overlapping end, combined with a frictional sleeve for holding them together, one of the parts of the shaft being hollow and the other having a solid portion against which a rod may be 65 inserted, to drive the ends apart, substantially as shown.

JOHN GILLESPIE.
